UNITED STATES PATENT OFFICE.

WALTER S. BOGLE, OF CHICAGO, ILLINOIS.

COAL-MINING MACHINE.

SPECIFICATION forming part of Letters Patent No. 716,181, dated December 16, 1902.

Application filed August 19, 1898. Serial No. 689,013. (No model.)

To all whom it may concern:

Be it known that I, WALTER S. BOGLE, of Chicago, in the county of Cook and State of Illinois, have invented certain new and useful Improvements in Coal-Mining Machines, of which the following is a specification.

This invention relates to coal-mining machines, and has for its object to provide an improved construction of track and form of wheels for the carriage or mount of the machine and an improved device for locking the carriage against longitudinal movement on the track when the machine is at work.

To these ends the invention consists in certain novel features, which I will now proceed to describe and will then particularly point out in the claims.

In the accompanying drawings, Figure 1 is a side elevation of a machine embodying my invention; Fig. 2, a plan view of the same with the tool or pick omitted; Fig. 3, a rear elevation, on an enlarged scale, partly in section, through the truck or way; Fig. 4, a vertical sectional view taken longitudinally through the center of the base or lower part of the carriage and also on an enlarged scale.

In said drawings, 10 represents the mining-machine proper, which is of a well-known type, preferably imparting a reciprocating motion to the tool or pick and which may be of any approved construction for this purpose, its particular structure forming no part of my present invention. This machine is provided with horizontal trunnions 11 at its sides, forming a transverse axis at right angles to the line of reciprocation of the tool or pick, upon which axis the machine may be swung so as to vary the height and angle to the horizontal of the cut on the machine.

10 The trunnions 11 are mounted in bearings 12 on the upper ends of a standard or support 13, which is U-shaped or in the form of a yoke, as most clearly shown in Fig. 3, to permit the body of the machine to swing freely 45 between the vertical arms of said standard.

The standard 13 is mounted upon a truck 14, with which it has a pivotal connection by means of a vertical pivotal axis 15. The truck 14 is provided with a circular flange 16, 50 forming a turn-table, and the standard is provided with a similar circular recess 17 in its base to fit upon the turn-table 16 and take

the strain from the pivot-bolt 15, which connects the standard and truck, at the same time giving a more extended bearing, so as 55 to provide a more efficient support and reduce friction. The truck 14 is provided with carrying wheels or rollers 18, which are preferably tapered or frusto-conical in shape, as shown in Fig. 3, and there is provided a suitable track or way in which said wheels or rollers travel and are held against vertical and lateral displacement. To this end the track or way is provided with lateral grooves 19, having inclined flanges 20, extending under the wheels or rollers 18 and similar inclined flanges 21, extending over said wheels or rollers. The inclination of the flanges corresponds, of course, to the inclination of the rollers. In the construction shown in the 70 drawings this track or way is composed of angle-bars 22 and 23, united at suitable intervals by yokes 24, the angle-bars being arranged in pairs one above the other, as illustrated in Fig. 3, and the yokes serving not only to connect 75 the members of each pair, but also to connect the pairs to each other. This track or way is carried upon suitable supporting-timbers 25, extending longitudinally under the same at each side thereof, the whole being connected 80 together so as to form a portable way or track, which may be moved from place to place as required. This track or way is provided, preferably along its central portion, with a fixed rack 26, and the truck which carries the machine is provided with a coöperating dog 27 to engage said rack and prevent extended motion of the truck and the machine carried thereby relatively to the track. This dog is preferably constructed in the manner shown 85 in detail in Figs. 1 and 4 of the drawings and comprises a suitable barrel or casing 28, pivoted at its forward end 29 to the truck-frame and having mounted within it so as to slide longitudinally therein the extensible portion 90 30, which carries the dog proper, 31. A spring 32, mounted within the barrel or casing, bears against the inner end of the extensible portion 30 and serves to thrust said portion and dog proper normally outward and rearward, 95 so as to hold the same in engagement with the teeth of the rack 26. A pin 33, extending from the barrel or casing through a horizontal slot 24 in the extensible portion 30,

serves to limit the longitudinal motion of this latter and also to prevent its rotation within the barrel or casing, thereby insuring a proper presentation of the dog to the teeth of the 5 rack. The dog proper, 31, may be provided with a pivoted link or handle 31^a, by means of which said dog may be conveniently raised and held out of engagement with the rack when it is desired to move the truck upon the 10 way or track.

It will be observed that my invention employs a form of rack wherein the lateral walls of the teeth are vertical, in conjunction with a dog having similar vertical sides, so 15 that when the dog and rack are in engagement the carriage is securely locked against movement in either direction. I also provide means for firmly securing or anchoring the track or way in position in the mine, and for 20 this purpose I prefer to employ the particular form of structure shown in Figs. 1 and 3 of the drawings. This consists of a yoke or bail 35, pivoted or hinged at or near the rear or outward end of the way or track and carrying 25 a hand-wheel 36, which is internally threaded to receive a correspondingly-threaded rod or bar 37, which forms an extension of the yoke 35. At the upper end of the rod 37 is provided a point or tip 38, which is toothed or 30 otherwise adapted to engage the roof of the mine when forced into contact with the same.

The anchoring device just described serves to secure the rear end of the track firmly in position, and may, as a rule, be sufficient for 35 properly holding the entire track. I prefer, however, to employ in conjunction therewith an anchoring device for the front of the track consisting of a spur or pointed projection 39, which is adapted to engage with the wall of 40 the mine in front of the machine and by such engagement lock the front end of the track against vertical movement.

The machine thus constructed and mounted 45 operates in the following manner: The track or way is moved to that portion of the mine where the machine is to be used and is firmly anchored in place by engaging the spur 39 with the wall and by swinging the yoke 35 into an upright or approximately upright position and rotating the hand-wheel or nut 36, so as to force the rod or bar 37 upward until its point or tip 38 engages the roof of the mine, and being forced firmly against the same serves to anchor or secure the track or 55 way firmly in position. The rod or bar 37 may be held against rotation by the hand of the operator while the hand-wheel 36 is being turned or suitable provision, such as a spline or groove connection between said rod or bar 60 and the yoke 35, may be made to positively prevent rotation of said rod or bar. The truck 14, mounted in the track or way, is then moved forward to bring the machine to the desired position relatively to its work, and 65 the dog 27, engaging with the rack 26, will positively prevent any motion of the truck and machine while in such engagement.

The spring 32 will, however, permit a certain amount of yielding of the truck under the shock of the blows delivered by the machine 70 when at work and will thus lessen the strain on the machine and its mount by acting as a cushion, thereby preventing wear and increasing the durability of the apparatus. The machine may be turned upon its vertical 75 pivot 15, so as to cut either directly in front or along either side or in any intermediate position, and by swinging the machine upon its trunnions 11 it may be made to alter its vertical range of work as desired, so that in 80 practice the machine may be caused to operate upon any part of the drift, either in front of it or at its sides, within a very large vertical range. The machine may of course be fed forward whenever necessary by disengaging the dog 27 from the rack 26 and giving to the truck or carriage the desired amount of movement in advance.

The construction of the way or track is such as to prevent any lateral displacement 90 of the truck therefrom and also such as to prevent its being displaced vertically either in an upward or a downward direction, so that the truck is firmly held in place to resist the recoil of the machine at whatever 95 angle to the plane of the track the machine may be working. If the way or track be so arranged as to have an inclination toward the work and the form of rack shown in Fig. 5 be employed, it is obvious that the machine 100 will be automatically fed forward along the track to the work by gravity and will be prevented from recoiling by means of the rack and dog provided for that purpose.

It is obvious that although I have described 105 the machine as a coal-mining machine its use is not limited to the mining of coal, as it may be used for mining or drilling material other than coal.

I claim—

1. In a mining-machine, the combination with a tool-head provided with lateral trunnions, of a carriage or truck in which it is mounted, a track on which said carriage may travel, and means for locking said carriage 115 in fixed position relatively to the track, said means comprising a rack disposed longitudinally of the track and between the rails thereof and a dog pivoted to the under side of the carriage and adapted to engage said rack 120 and thereby hold the carriage against travel in either direction, substantially as described.

2. In a mining-machine, the combination with a tool-head provided with lateral trunnions, of a carriage or truck in which it is 125 mounted, a track on which said carriage may travel, and means for locking said carriage in fixed position relatively to the track, said means comprising a rack disposed longitudinally of the track between the rails thereof 130 and having teeth provided with vertical side walls and an elastically-supported dog pivoted to the under side of the carriage, the nose of said dog also having vertical side walls and

engaging between adjacent teeth of the rack, substantially as described.

3. In a mining-machine, the combination with a tool-head provided with lateral trunnions, of a carriage or truck in which it is mounted, a track on which said carriage may travel, and means for elastically locking said carriage at any desired location along said track, said means comprising a dog constructed in two telescoping parts having a spring interposed therebetween and cushioning their relative longitudinal movements, said dog being pivoted at one end to the under side of the carriage, and a rack disposed longitudinally of the track and between the rails thereof, and adapted to be engaged by the free end of the aforesaid dog, substantially as described.

4. In a mining-machine, the combination

with a mining-tool and a carriage supporting the same, said carriage having wheels or rollers frusto-conical in shape and of outwardly-increasing diameter, of a track therefor, the parallel rails or ways of said track each comprising a pair of angle-bars disposed one above the other so as to form a groove or way therebetween corresponding to the frusto-conical shape of the wheels, and yokes disposed at suitable intervals along the track and serving to connect the angle-irons of each pair and also to connect the pairs to each other, whereby the carriage is secured against both vertical and lateral derailment, substantially as described.
